UNITED STATES PATENT OFFICE

ZEBULON L. CHADBOURNE, OF LOS ANGELES, CALIFORNIA

PROCESS FOR WEAVING HAMMOCKS

Application filed April 7, 1930. Serial No. 442,128.

My invention relates to hammocks or other devices where a weaving mesh is used and more particularly to the process of producing the same, whereby said hammock or other 5 devices may be completed in a much shorter time than possible by known processes, said process being carried into effect by the use of the hands only, thereby providing a hammock which is not only made in a much shorter 10 time than has heretofore been done, but a novel form of hammock is constructed which is exceedingly attractive in appearance, as well as inexpensive, and at the same time affords comfort and safety to the individual 15 using the same.

It accordingly is an object of my invention to provide a novel form of hammock and process for constructing the same, which is carried into effect by the use of the hands 20 only, said process consisting in mounting the warp strands, which may be of twine, rope, fiber, or the like, on a framework in such a manner that said strands may be quickly applied thereto and removed therefrom, the 25 woof strands, if preferred being of different color or colors than said warp strands, said woof strands being anchored to said framework and then selectively and by hands only passed under and over any preferred number 30 of said warp strands, suitable spacing means, adapted to be placed across said warp strands on said framework, functioning to permit the reverse weaving of the strands, so that not only a strong web is obtained, but 35 a hammock of attractive appearance is had.

It is also within the province of my invention to provide a novel spreader construction for the hammock, in which the supporting strands for the web are mounted in and 40 secured to said spreader, which strands are knotted in a suitable manner, and then looped to the knotted ends of the web, and finally secured to a suitable hammock supporting 45 means, such as a ring, hook or the like, the ends of said supporting strands being secured thereto in any way in practice preferred.

The above and further objects and advantages of my invention, as will hereinafter 50 more fully appear, I attain by the process

and construction described in the specification and illustrated in its preferred form on the drawings, forming a part of my application.

Reference is had to the accompanying 55 drawings, in which similar reference characters denote similar parts. In the drawings,

Fig. 1 is a plan view of a loom which may be employed in practicing my invention showing the warp and woof strands in place 60 thereof during the initial step of weaving the hammock;

Fig. 2 is a plan view of the loom shown in Fig. 1 but illustrating the positions of the warp and woof threads during the second 65 step of weaving the hammock;

Fig. 3 is a detail view of a section of the hammock after weaving but before the same is removed from the loom;

Fig. 4 is a perspective view of the spreader 70 bar which may be employed in connection with my hammock construction;

Fig. 5 is a detail view illustrating the manner of securing the ends of the hammock threads and the cords extending over the 75 spreader bar; and

Fig. 6 is a detail sectional view through the spreader bar, illustrating the manner of securing the cords in place thereon.

Describing my invention more in detail, in 80 its broader aspects said invention comprises the production of a novel form of hammock by a novel process, carried into effect by the use of the hands only, whereby said hammock may be made with minimum expenditure of 85 material and time, said process consisting of mounting the warp strands, such as twine, fibre, grass, rope and the like, of the same or different colors, in a suitable way on a framework, said strands being preferably detachably associated with a suitable supporting means, such as pegs, the woof strands, of a 90 different or varying color, to be interwoven with said warp strands by the use of the hands only, under and over said warp strands, selectively, as desired, and then reversed by means of suitable spacers so that the size of the mesh may be varied at will 95 positioned across said warp strands, said operation being continued until the web is com- 100

pleted, after which the ends of both of said strands, are gathered together selectively and knotted to form an attractive color scheme.

- 5 The knotted ends are looped with supporting strands, which strands are then passed through grooves in suitable spreaders, which strands are held in position in said grooves by a suitable means, such as a set of wire rods
10 passed through any preferred form of securing means, such as staples, said supporting strands being then secured in any desired way to the hammock supports, such as rings, hooks and the like.
15 More specifically, the structure for carrying my novel form of process into effect comprises a suitable framework 2, which may be in rectangular form, and held together in any preferred way, and, if desired, made of wood, for the sake of economy.

Mounted upon the top bar of the framework 2 and spaced therealong are a plurality of pegs or other supports 4 extending above the surface of the bar 3 to engage and hold 25 the warp strands 10 from which the hammock is to be woven. A second set of pegs are provided, extending in spaced relation along the top bar 3 of the frame 2 and these pegs 5 are, preferably, above the line of the first mentioned set of pegs 4. The pegs 5 are adapted to receive and hold the woof strands 14. The lower end of the frame includes a lower cross bar 11 to which is secured a plurality of pegs 4' for receiving the warp 30 strands 10 and a plurality of similar pegs 5' for receiving the woof strands 14.

The first step in weaving a hammock in accordance with my invention is to secure one end of the warp strands or cord 10 to one of the pegs 4, as is indicated by the knot 12 and then winding the woof strands or cord 10 upwardly and downwardly across the loom 2 engaging the strand on the pegs 4 and 4' at the top and bottom of the loom, respectively, to cover the entire loom with the strands following a convolute path from top to bottom of the loom.

The woof strands 14 are brought into play and may be wound over the pegs 5 and 5' to form a second series of threads or cords covering the entire loom and lying above the warp strands which have already been placed upon the loom.

As is indicated in Fig. 1, the lower pegs 5', over which the lower loops of the woof strands 14 are to be wound, are spaced considerably below the pegs 4' on which the warp strands are wound, thus providing some extra length to each of the coils of the 60 woof strands when in place upon the loom.

The next step is to prepare the woof strands for weaving in and out upon the warp strands and this is accomplished by cutting each of the lower loops of the warp strands 65 at the pegs 5', this operation being illustrated

in Fig. 2 showing the woof strands cut as is indicated by the reference character 13. Thus the woof strands are prepared for weaving.

Referring again to Figs. 1 and 2, it will be observed that a plurality of hooks 6 are spaced along the side rail 7 of the loom 2, these hooks preferably being pointed upwardly and arranged in spaced relation to each other along the rail 7 to receive suitable spacer bars 8 which may be engaged with the hooks. I have illustrated one of the spacer bars 8 as being provided at the top of the loom 2, its purpose in this position being to assist in maintaining the warp and woof strands against accidental displacement from the pegs 4 and 5. The spacing of the hooks 6 may be suitably selected to conform with the length of the mesh which is desired and will be employed as hereinafter described.

The operator or weaver now grasps any preferred number of woof strands 14 in one hand and then passes the left-hand warp thread designated by the character 14a over certain of the warp strands and under certain others of the warp strands. For example, as is indicated in Fig. 3, the first strand 14a will be passed over the third and fourth warp strands, indicated by the reference characters 10c and 10d, respectively, and under the second and first warp strands 10b and 10a, respectively.

The next left-hand woof strand 14b may then be passed over the first and fourth warp strands 10e and 10d respectively, and under the third and second warp strands 10c, and 10f, respectively. This process is repeated until all of the woof strands have been woven through the warp strands. At this time the second spacer bar 8a may be placed in position upon its hooks 6 so as to pass over all of the warp strands and under the now loose ends of the woof strands and the woof strands may now be woven back toward the right-hand end of the loom 2 in the same manner as these strands were woven to the left in the hereinbefore described operation.

When all the strands have been woven in one direction another spacer bar may be placed in position and the warp strands woven in the reverse direction and this process may be repeated until the entire loom is covered with meshes, as is indicated in Fig. 3.

The finished web is now removed from the framework 2, and the ends of the warp and woof strands knotted together selectively and in any desirable and artistic manner (see Figs. 4 and 5) after which the web supporting strands 16, which may be of the same or different color than either of the warp and woof strands and preferably of heavier or more rigid materials, may be looped through said knots by means of a half hitch 18 or

other form of loop or knot, after which said supporting strands are passed through the grooves 20 in the hammock spreaders 22, and then gathered together at the ends and looped

5 over and knotted or secured in any preferred way to the hammock supports, such as the conventional form of hooks, rings and the like.

A convenient way of holding the strands 10 16 in position in the grooves 20 of the spreaders 22 is shown in Figs. 4 and 6, which may comprise a set of wire rods 24, preferably two in number, and positioned as seen in Fig. 3, said rods being secured to the spreaders 22 by any suitable means, such as the staples 26. This forms not only an inexpensive means for holding the web supporting strands in position on the spreaders 22, but is an extremely efficient and speedy way of 15 20 doing so.

Each side of the hammock has a selvage strand 28, which, if desired, may be a thicker warp strand or cord, or said selvage may be formed in any other manner preferred.

25 It will be seen that my novel form of hammock, when completed, will permit the user to rest comfortably therein, when sitting and reading, or lying prostrate, it being impossible in all positions for said user to fall therefrom.

In accordance with the provisions of the patent statutes, I have described the principle of operation of my invention together with the apparatus and process which I now 35 consider to represent the best embodiment thereof; but I desire to have it understood that the apparatus and process shown are only illustrative, and that the invention can be carried out by other means.

40 I claim as my invention:

1. The process of weaving hammocks which consists in laying out a plurality of parallel warp strands, anchoring said warp strands at each end thereof, laying out a plurality of 45 woof strands superimposed upon said warp strands and running parallel thereto, and individually and by hand weaving said woof strands over and under said warp strands while said warp strands remain anchored.

50 2. The process of weaving hammocks which consists in laying out a plurality of parallel warp strands by forming a continuous length of warp material into a plurality of parallel convolutions, anchoring said warp strands at

55 the ends of each loop forming the convolution, winding a continuous length of woof material to form a series of convolutions substantially paralleling the warp strands and superimposed upon said warp strands, 60 anchoring one end loop of each convolution of said woof strands, cutting the other end of each of the convolutions of said woof strands, and individually and by hand weaving said woof strands over certain of said 65 warp strands and under adjacent warp

strands, back over said second named warp strands and under said first mentioned warp strands and repeating throughout the length of said warp strands.

3. The process of weaving hammocks which 70 consists in laying out a plurality of parallel warp strands by forming a continuous length of warp material into a plurality of parallel convolutions, anchoring said warp strands at the end of each loop forming the convolution, winding a continuous length of woof material to form a series of convolutions substantially paralleling the warp strands and superimposed upon said warp strands, anchoring one end loop of each convolution of said woof strands, cutting the other end of each of the convolutions of said woof strands, individually and by hand weaving said woof strands over certain of said warp strands and under adjacent warp strands, back over said 75 second named warp strands and under said first named warp strands and repeating throughout the length of said warp strands, and inserting a transverse spacer above said warp strands and below said woof strands between the point of reversal of the weaving of each of said warp strands.

4. The process of weaving hammocks which 80 consists in laying out a plurality of parallel warp strands by forming a continuous length of warp material into a plurality of parallel convolutions, anchoring said warp strands at the ends of each loop forming the convolution, winding a continuous length of woof material to form a series of convolutions substantially paralleling the warp strands and superimposed upon said warp strands, anchoring one end loop of each convolution of said woof strands, cutting the other end of each of the convolutions of said woof 85 strands, and individually and by hand weaving said woof strands over certain of said warp strands and under adjacent warp strands, back over said second named warp strands and under said first mentioned warp 90 strands and repeating throughout the length of said warp strands, and binding the ends of the fabric so produced by tying a supporting strand through each of a plurality of adjacent end loops of both said warp 95 strands and said woof strands throughout the width of said fabric.

In testimony whereof I have signed my name to this specification.

ZEBULON L. CHADBOURNE. 100
